2,509,815

ELECTRIC CURRENT AND VOLTAGE INDICATOR

Filed July 24, 1945

FIG. 2

INVENTOR.
ROSS W. ELLIOTT
BY *A. B. Bowman*
ATTORNEY.

UNITED STATES PATENT OFFICE

2,509,815

ELECTRIC CURRENT AND VOLTAGE
INDICATOR

Ross W. Elliott, San Diego, Calif.

Application July 24, 1945; Serial No. 606,824

1 Claim. (Cl. 175—183)

1

My invention relates to an electric current and voltage indicator, more particularly of the portable type adapted to be carried on the person of an electrician or other service man and the objects of my invention are:

First, to provide an instrument of this class which indicates actual values of current and voltage without the use of a delicate and expensive meter;

Second, to provide an instrument of this class in which an electronic tube is used and so arranged that it will operate at the ignition point indicating voltage or current in accordance with the adjustment of a variable resistor forming a part of said instrument;

Third, to provide an instrument of this class in which an automatic reset protects it from over loads to which it may be subjected inadvertently;

Fourth, to provide an instrument of this class in which all of the exterior portions are properly insulated for the protection of the operator;

Fifth, to provide an instrument of this class which is very compact, light in weight and very durable;

Sixth, to provide an instrument of this class which will provide safety to men working at the various electrical trades; and

Seventh, to provide an instrument of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference thereon forming a part of this application in which:

Figure 1 is a side elevational view of my electric current and voltage indicator showing portions thereof broken away and in section to amplify the illustration and further showing by dash lines varying positions of parts and portions thereof; Fig. 2 is an edge elevational view thereof and Fig. 3 is a schematic view of the wiring of my electric current and voltage indicator.

Similar characters of reference refer to similar parts and portions throughout the several views of the drawings:

The casing members 1 and 2, transformer portions 3 and 4, rheostats 5, voltage conductors 6 and 7, resistors 8 and 9, neon tube 10, control knob 11 and transformer control spring 12 con-

stitute the principal parts and portions of my electric current and voltage indicator.

The casing members 1 and 2 are made of insulation material and the casing member 1 is the boxlike casing in which is rigidly mounted the transformer portion 3 having an L-shaped laminated core 3a engageable with the laminated core 4a of the transformer portion 4 which is rigidly connected to the casing member 2. This casing member 2 forms the side edge of my electric current and voltage indicator and this casing member 2 is shiftable as indicated by dash lines in Fig. 1 of the drawings. The core portion 4a of the transformer portion 4 is L-shaped and the end portion 4b thereof is shiftable mounted in the frame portion 3b about the inner end of the core portion 3a of the transformer 3. It will be noted that the end portion 4b of the core portion 4a engages the end portion 3c of the core portion 3a and that the spring 12 maintains the end portion 4b and 3c in engaged relation to each other, thus pressure exerted on the upper end portion 2a of the casing member 2 causes the transformer portion 4, together with the casing member 2 to pivot, as shown by dash lines in Fig. 1 of the drawings separating the contact ends 4c and 3d of the transformer portion cores 4a and 3a respectively.

Referring now to the wiring diagram in Fig. 3 of the drawings, the voltage conductors 6 and 7 are connected to mixed resistors 8 and 9 respectively which have a value of approximately seventy-five thousand ohms. In circuit with these resistors 8 and 9 is the rheostat 5 which is a two megohms variable resistor rotatively operated by the control knob 11 on which are the voltage and ampere scales cooperating with the pointer 11a secured on the casing 1.

The neon tube 10 is placed behind a window 10a in the said wall of the casing 1, as shown best in Fig. 1 of the drawing and is in circuit with the windings of the core portions 3a and 4a of the transformer portions 3 and 4, as shown in Fig. 3 of the drawings.

It will be here noted that the transformer portions in cooperative relation, as shown, form a split core transformer.

The operation of my electric current and voltage indicator is substantially as follows: Assuming that an electrician wishes to read the current in amperes, the portion 2a of the casing 2 is depressed causing the core portion 4a of the transformer portion 4 to shift to the dash line position, as shown in Fig. 1 of the drawings, permitting the insertion of the wire A between

the ends 4c and 3d of the core portion 4a and 3c respectively, as shown in Fig. 1 of the drawings. When the wire A is so positioned, the transformer control spring 12 forces the core portion 3a and 4a together forming a core path for the magnet field around the wire A. In order to indicate the current passing in connection with the wire A the control knob 11 is turned clockwise until the neon tube 10 glows through the window 10a. The amperage is then read directly at the point on the indicator 11a in connection with the amperage scale on the control knob 11. When it is desired to make a test for voltage, the voltage conductors 6 and 7 are connected to the circuit in question and the control knob 11 is turned clockwise until the neon tubes 10 glow, then the voltage is read directly at the point of the indicator 1a on the voltage scale on the control knob 11.

Though I have shown and described a particular construction, combination and arrangement of parts and portions, I do not wish to be limited to the particular construction, combination and arrangement, but desire to include in the scope of my invention the construction, combination and arrangement substantially as set forth in the appended claim.

Having thus described my invention, what I claim as new and desire to secure by Letters Patent is:

In an electric current and voltage indicator of the class described, the combination of a casing, a split core current transformer having core portions therein pivotally mounted relatively to each other, each of said casings having an extending laminated core portion engageable with each

other, a spring tending to force the extended portions of said core portions together, a variable resistor in circuit with the windings of said core portions across conductors thereto, a control knob in connection with said variable resistor having calibrations thereon and arranged to actuate the movable contact of said variable resistor, a neon tube connected across said variable resistor and said core portions, said neon tube intermediate said variable resistor and said transformer core portions for indicating the ignition point common to the amperage value of current passing in connection with the wire inserted between said extending core portions of said transformer, voltage conductors and fixed resistors in connection with said voltage conductors in circuit with said variable resistors and said transformer core portions.
